(57) **CLAIM**

The ornamental design for a ring game base, as shown and described.

DESCRIPTION

FIG. 1 a rear elevational view of a ring game base showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top front perspective view thereof;

FIG. 8 is a top plan view thereof, showing an alternate display on the base; and,

FIG. 9 is a top front perspective view of FIG. 8.

The broken lines showing of a cord is for illustrative purpose only and forms no part of the claimed design.
